UNITED STATES PATENT OFFICE.

GEORGE V. K. GREENE, OF NEW YORK, N. Y., ASSIGNOR TO E. ARDEN NOBLETT,
OF NEW YORK, N. Y.

ELECTRIC HEATER.

No. 910,191.

Specification of Letters Patent.

Patented Jan. 19, 1909.

Application filed February 19, 1908. Serial No. 416,757.

To all whom it may concern:

Be it known that I, GEORGE V. K. GREENE, a citizen of the United States, residing at the city of New York, county of New York, and State of New York, have invented certain new and useful Improvements in Electric Heaters, of which the following is a specification.

My invention relates to electric heaters and particularly to those wherein an electric current traverses, during its course, a material of high resistance forming a heating element, it thereby rendering said material hot or incandescent, the object of my invention being to provide a heater wherein the heating element shall be entirely protected from the oxidizing action of the air or from other damage.

Other objects of my invention are to provide means whereby a heating element of great area and high resistances may be used; to provide means whereby the said heating or current-resistant material may be used in a granular or powdered form; to provide a heater wherein the heating element is entirely protected from contact with the operator, and to provide a heater wherein all danger of short-circuiting is absolutely avoided.

To these ends my invention consists in the construction and arrangement of parts as shown in the drawings and specifically set forth in the appended claims.

In the drawings, Figure 1 is a plan or inside face view of one section of my heater, forming the base plate, the other section or covering plate being removed. Fig. 2 is a plan view of the inside face of the covering section. Fig. 3 is an enlarged fragmentary plan of a corner of the base plate. Fig. 4 is an enlarged fragmentary view of one corner of the inside face of the covering section. Fig. 5 is a cross section thereof on the lines $x-x$ (Fig. 3). Fig. 6 is a cross section on line $z-z$ (Fig. 5).

Like characters in all the several views designate like parts.

2 designates a base plate molded or otherwise formed of insulating material such as unglazed porcelain, "American lava", etc. I do not limit myself to any specific material, the only requirement being that it shall insulate the heating element and its terminals and that it shall have a high degree of resistance to heat. This plate is of any

desired thickness and is provided on its inner face with a continuous channel (3). This channel may be formed therein when the plate is molded. The channel (3) is adapted to contain the heating element and may be of any required depth and width. I have found that a channel three-eighths of an inch deep and one-quarter of an inch wide gives very excellent results. I merely give these figures for the sake of clearly demonstrating the comparatively large size of the heating element.

In order to obtain the greatest length of the heating element and therefore the greatest heating area, the channel preferably extends in a number of turns backward and forward across the base plate 2, in the manner shown in Fig. 1. The ends of the channel might extend directly to that edge of the plate adjacent to the nearest coil or bend of the channel, but I would deem it preferable to carry the channel around so that the ends will extend outward to the edge of the plate on the same side, as shown in Fig. 1.

The channel 3 is filled with material designated by the numeral 4 which will offer resistance to the passage of an electric current and which will thereby become heated to the degree required on the passage of a current. The material filling this channel I term the heating element. I may use any material desired as the resistant heating element and in any form; preferably, I use a resistant in the form of powder which is filled comparatively loosely into the channel or is compressed therein.

The heating element or resistant 4 does not extend to the margin of the base plate, that is to the outside of the casing formed by the base plate and covering, but stops short of the margin at the points marked $y-y$ in Fig. 1. Terminals 5, 5' preferably are of brass and are inserted into the ends of the channel and are in contact with the heating element; the exterior ends of the terminals being adapted to be connected in circuit with any source of electricity.

The base plate and its heating element are covered by a covering plate 6 which fits upon the base plate and is fastened tightly thereon by screws or bolts which pass through the opening 7 on the margins of both plates. This covering plate is preferably of unglazed porcelain or other material of high resistance as above referred to. This

plate might be made of stamped sheet metal and the heating element insulated therefrom by sheets of mica or other means.

The inner face of the covering plate 6 fits 5 tightly against the face of the base plate 2 and in order to prevent the entrance of air between the faces of the plates, cement is placed around the margins of the plates between their adjacent faces, thus completely 10 filling the spaces and rendering the joint air tight. To make the joint still further air tight I have provided one of the plates with a marginal rib 7' and the other has a marginal groove into which this rib will fit.

15 In the drawings, I have shown the upper plate with the marginal rib 7' and the lower plate with the marginal groove 8. The rib and groove are preferably made with inclined sides. Cement may be placed in this 20 groove, but preferably I place cement between the rib and the edge of the plates. Thus, when the two plates are in place one upon the other cemented as just described, the rib on one plate engaging with the 25 groove in the other, the heating element will be entirely isolated from contact with the air and oxidation of the element and its consequent deterioration will be absolutely prevented.

30 The exterior of the base plate 2 may be made with a groove around its edge or any desired portion thereof so that the heater may be supported on a suitable frame. In Fig. 5 I have shown an angle iron support 35 engaging with this groove. As my heater is adapted to be used in a large variety of circumstances and under many different conditions I have not deemed it necessary to show any particular variety of supporting 40 frame as that is not within the scope of this invention.

While I have shown the channel 3 as being made entirely in the base plate 2 I wish it understood that said channel might be 45 formed partly in the top plate and partly in the base plate. I do not wish to be limited to any of the details of construction shown nor to any specific material. The heating element may be formed of any desired resi- 50 stant material, such as powdered carbon and the channel may traverse the plates in any desired figure. The channel, however, should be continuous for each heating surface.

55 The advantages of my invention are as follows: Because of the fact that the heating element is supported along its entire length the heating element may be of great extent and a very large cross-section, though formed 60 of material far weaker and less rigid than would be possible were the heating element unsupported and uninclosed. The heating element does not deteriorate for the reason that it is entirely inclosed and protected from 65 contact with the air. This is a most im-

portant point, adapted not only to prevent extraneous damage to the heater but also preventing oxidation. Plates of this character are adapted to be easily handled, used in any position desired and to a large variety 70 of circumstances where it would be impossible to use unprotected heaters. The device is simple, of a high heating capacity and may be much more easily used than heaters of ordinary construction.

75 A further advantage resulting from the use of my invention is that there is no danger of short circuiting. The faces of the two plates within which the heating element is inclosed absolutely contact one with the other so that 80 the electricity cannot possibly pass. Neither can a short circuit be formed by the heating element being brought adjacent to metal or other conducting material. This is one of the most prominent faults of electric heaters 85 as ordinarily constructed and to it is due a large number of accidents. By inclosing the heating element within these non-conducting plates, all chance of short circuiting is absolutely prevented and under no circumstances 90 can fire occur. Of course, it is understood that the covering plate, and indeed for that matter, the base plate to a somewhat lesser extent on account of its thickness, becomes heated by this contact with the incandescent 95 or heating element 3.

Having described my invention what I claim is:

1. An electric heater comprising two conjoined plates of non-conducting material, one 100 of said plates being formed with a continuous channel, the ends of said channel opening to an edge of said plate, said channel being filled with a heating element of current resisting material, and means for engaging 105 said heating element with a source of electricity, one of said plates being formed with a rib adjacent to its margin, the other of said plates being formed with a groove into which the rib is adapted to project and material filling the space between the plates exterior to said rib. .

2. An electric heater comprising a flat, hollow case formed in two parts adapted to be fastened together the peripheral margins of 115 said plates having contact with each other, a heating element composed of electric current resisting material contained in the space between the said plates and connected with a source of electricity, and a cementing material located between the plates on the contacting faces of the margins thereof.

3. An electric heater comprising a base plate of non-conducting material having on the inner face thereof a continuous channel 125 extending backward and forward across the face of the plate and to one edge of the plate and a covering plate whose inner face is adapted to contact with the face of the base plate, means for holding the covering plate 130

in air-tight contact with the base plate around its entire edge, a heating element composed of an electric current-resisting material filling the channel of the base plate, and terminals contacting at their ends with the heating element and projecting to the edge of the base plate.

5 In testimony whereof, I have signed my

name to this specification in the presence of two subscribing witnesses, this 11th day of 10 February 1908.

GEORGE v. K. GREENE.
